CROSS-TALK SUPPRESSION

John E. Boughtwood, Halesite, N. Y., assignor to The Western Union Telegraph Company, New York, N. Y., a corporation of New York

Application April 17, 1951, Serial No. 221,470

10

5 Claims. (Cl. 179—15)

The present invention relates to pulse modulation systems and more particularly to suppressing cross-talk between the channels thereof.

In pulse modulation systems wherein the transmitting time is divided into discrete intervals divided among the different intelligence channels, it is important that the signals representing intelligence samples do not overlap, or if they do overlap that such overlapping is suppressed before the intelligence samples are applied to the respective receiving channels. If such overlapping is not suppressed, intelligence intended for one channel will appear as interference in one or more other channels. This interference, which is commonly termed cross-talk, may be sufficiently strong to render the system unusable or at least seriously to impair the operation thereof.

The chief cause of cross-talk in pulse modulation systems is distortion of the pulse wave shapes resulting from the non-linear phase-frequency and amplitude-frequency characteristics of the transmitting medium and the filters and other circuits of the transmitter and receiver.

Accordingly, it is an object of the invention to provide means for suppressing cross-talk between channels of a pulse modulation system.

More particularly, it is an object of the invention to provide means for suppressing cross-talk in a pulse modulation system resulting from distortion of the received pulse wave shapes.

Another object of the invention is to provide simple and easily adjustable apparatus for suppressing cross-talk between channels of a pulse modulation system.

Further objects of the invention will appear from the following description.

In accordance with the invention, these objects are achieved by providing means to shift the phase of a portion of the high frequency components of the received pulses to correct the shape of the leading edges of the received pulses, differentiating the received pulses to correct the shape of the trailing edges thereof, and by adding to the received pulses a modulation component of equal amplitude and in phase opposition to the long term cross-talk present in the respective receiving channels.

The invention will now be described in greater detail with reference to the appended drawing in which:

Fig. 1 illustrates the receiver of a pulse amplitude modulation system;

Figs. 2, 3 and 4 are diagrams illustrating the operation of the circuit of Fig. 1;

Fig. 5 illustrates the production of long term cross-talk; and

Fig. 6 shows a circuit for suppressing long term cross-talk.

Referring now to the drawing and more particularly to Fig. 1, the receiver illustrated therein is substantially the same as the receiver of the pulse amplitude modulation system described in my copending U. S. patent application Serial No. 221,469, filed concurrently herewith and now Patent No. 2,672,517.

2

The receiver of Fig. 1 comprises a radio receiver 10, the output of which is applied to an amplifier and low pass filter 11, the output of which is, in turn, derived from a potentiometer 12 and applied to the control grid 13 of an amplifier tube 14 through a capacitor 15. The amplified output of tube 14 is applied to control grid 16 of an electron discharge tube 17 through a coupling capacitor 18. Anode 19 of tube 17 is coupled to a source of positive potential through a resistor 20, while cathode 21 is coupled to ground through a resistor 22. Resistors 20 and 22 are preferably equal in magnitude so that the signal voltages developed thereacross will be substantially equal and in phase opposition.

One end of a variable capacitor 23 is connected to anode 19. One end of a variable resistor 24 is connected to cathode 21. The free ends of capacitor 23 and resistor 24 are connected together and to the control grid 25 of an electron discharge tube 26 through a coupling capacitor 27.

Assuming a signal voltage having a given frequency applied to control grid 16, the phase of the voltage applied to control grid 25 can be adjusted through substantially 180° by varying the respective values of capacitor 23 and resistor 24 because the voltage applied to grid 25 is determined by the relative proportions and phase relationships of the voltages at anode 19 and cathode 21 applied to grid 25. If the signal voltage applied to control grid 16 comprises a plurality of frequency components, the phase relationships between the components can be varied by varying the relative values of capacitor 23 and resistor 24.

Anode 28 of tube 26 is coupled to a source of positive potential through a resistor 29. Cathode 30 of tube 26 is coupled to ground through two series connected potentiometers 31 and 32. The tappings of potentiometers 31 and 32 are coupled to ground through variable resistor 33 and variable capacitor 34 and variable resistor 35 and variable capacitor 36, respectively. Circuit elements 31 through 36 constitute a differentiating network, the function of which will be described more fully hereinafter.

Anode 28 is coupled to ground through a variable capacitor 37 and to a synchronous gate 38 through coupling capacitor 39. Cathode 30 is coupled to frequency divider system FD, which is in turn coupled to synchronous gate 38 and to an electronic receiving distributor 40. The outputs of receiving distributor 40 are applied, respectively, to detector-amplifiers 41A through 41H. The outputs of detector-amplifiers 41A through 41H are applied, respectively, to output terminals OA through OH through low pass filters 42A through 42H, respectively. The output of detector-amplifier 41A is also applied to a band pass filter 43 which is coupled to distributor stepper 44. The output of stepper 44 is applied to frequency dividers FD.

The circuits of the detector-amplifiers 41A through 41H will be described more fully hereinafter in connection with Fig. 6. The circuits and functions of synchronous gate 38, frequency divider system FD, receiving distributor 40, low-pass filters 42A through 42H, band pass filter 43 and stepper 44 are fully described in my copending patent application referred to hereinbefore.

In Fig. 2A there are illustrated idealized band pulses for application to amplifier tube 14 of Fig. 1. These pulses are substantially identical to the sending distributor output after slicing in a gating circuit as described in my said copending patent application. In Fig. 2 the pulses for channels A through E are indicated, channel C having modulation present therein indicated by crosshatching. The pulses of Fig. 2a contain a large number of harmonic components, so that transmission through circuits and media having restricted band width will produce changes in wave shapes.

Fig. 2b indicates wave shapes for the pulses which might actually be present at the output of amplifier and filter 11. It will be observed that the steep leading and trailing edges of the pulses of Fig. 2a have been lost. Furthermore, the waves corresponding to the different channels overlap, which will tend to produce cross-talk in the outputs of receiving distributor 40. Fig. 2c illustrates the wave shapes of Fig. 2b without modulation in channel C. The time intervals outlined by dashed lines A' through E' indicate the portions of the waves sliced by synchronous gate 38. In other words, only those portions of the pulses lying within the dashed lines will be applied to receiving distributor 40. Use of a gating circuit materially reduces cross-talk, but, as is evident from Fig. 2c, overlapping during the gating intervals still occurs.

Fig. 3a illustrates the wave shape of the channel C pulse at the output of filter 11 and the gating intervals B', C' and D' of channels B, C and D, respectively. The leading and trailing edges of pulse C have sloping shapes instead of the desired sharp rise and fall of Fig. 2a. The principal causes of this loss of desired shape of the leading edge are the non-linear amplitude-frequency and phase-frequency characteristics of the circuits and media through which the pulse has been transmitted. In particular, restricted bandwidth and limited transient responses produce variations in amplitude and phase of the high frequency pulse components with respect to the low frequency pulse components.

Adequate suppression of cross-talk does not require the received pulses to be returned to their ideal shapes, but only that the pulse amplitude of a given channel be sharply reduced during the gating intervals of other channels. This is accomplished with respect to the leading edge of the waves by shifting the phase of a portion of the high frequency components. Correction of the leading edge of the waves is accomplished in the circuit of Fig. 1 by tube 17 and its associated phase shifting circuit.

The phase-frequency characteristic of this phase shifting circuit is illustrated in Fig. 3b, which is a plot of phase vs. frequency. If the phases at anode 19 and cathode 21 be assumed as +90° and -90°, respectively, at low frequencies capacitor 23 will appear as an open circuit, so the voltage applied to grid 25 will have a phase of -90°. As the frequency is increased, the effect of capacitor 23 becomes more pronounced, shifting the phase of the voltage applied to grid 25. At high frequencies, capacitor 23 acts substantially as a short circuit, so that the phase of the voltage applied to grid 25 will be substantially +90°. When pulse C is applied to the phase shifting network, the different frequency components thereof will be shifted in phase in accordance with the characteristic shown in Fig. 3b. These phase shifted components vary the wave shape of pulse C, producing a corrected wave shape at the leading edge of the wave.

The corrected pulse RC is shown in Fig. 3c. From Fig. 3c it can be seen that the leading edge of wave RC does not appear during the gating interval B'. This phase shifting circuit will have a negligible effect on the trailing edge of the wave.

Fig. 3d is a vector diagram of the voltages across the elements of the phase shifting circuit. The phase of resultant voltage VR, which is the voltage developed between the junction of resistor 24 and capacitor 23 and ground, can be varied through 180° along locus curve L by relative adjustment of resistor 24 and capacitor 23, which adjustment varies voltages V24 and V23 in magnitude and phase. Capacitor 23 renders the circuit frequency sensitive, so that the phase shift produced can be materially different at high and low frequencies, as indicated in Fig. 3b.

Corrected wave RC still overlaps gating interval D' of channel D, as shown in Fig. 4a. This overlap can be

suppressed by differentiating pulse RC to produce a pulse TC, and combining pulse TC with pulse RC to produce pulse R'C. The pulses RC, TC and R'C are illustrated in Figs. 4a, 4b and 4c, respectively. The differentiating network for producing the trailing edge correction comprises circuit elements 31 through 36 in the cathode circuit of tube 26. This differentiating circuit also tends to steepen the leading edge of pulse R'C, as shown in Fig. 4c.

The trailing edge correcting circuit will not be as effective if the trailing edge of pulse C exhibits oscillatory excursions, as illustrated in Fig. 4d. However, these oscillatory excursions, as illustrated in Fig. 4d, are compensated for in the circuit of Fig. 1 by partially de-coupling anode 28 with respect to high frequencies by means of capacitor 37. Capacitor 37 effectively converts the wave of Fig. 4d into the wave of Fig. 3a.

Cross-talk may also be produced through the suppression of low frequency components of the pulses. In Fig. 5a there is shown an ideal pulse without modulation. Fig. 5b illustrates the pulse of Fig. 5a after having passed through a network which strongly attenuates the lower frequency components. It will be noted that the pulse of Fig. 5b exhibits a negative excursion of relatively short duration and relatively large amplitude. If suppression of low frequency components is reduced through careful design of the system, a pulse as shown in Fig. 5c in which the negative excursion is exaggerated, will result. This negative excursion is of relatively small and substantially constant amplitude but long duration relative to the sampling intervals. Distortion of this type yields long term cross-talk, that is, cross-talk appearing in each of the channels with substantially equal amplitude.

In accordance with the invention, long term cross-talk is suppressed by adding a modulation component of equal amplitude and in phase opposition to the long term cross-talk in each of the receiving channels. A suitable circuit is shown in Fig. 6, which illustrates in detail the detector-amplifier stages 41A through 41H of Fig. 1.

Detector-amplifier stage 41A comprises a diode rectifier 50, the cathode 51 of which is coupled to ground through a resistor 52. The channel A signal pulses are applied to cathode 51 through coupling capacitor 53. Anode 54 of diode 50 is coupled to control grid 55 of amplifier tube 56 through a coupling capacitor 57. Anode 54 is also coupled to ground through the parallel combination of capacitor 58 and resistor 59. Cathode 60 of tube 56 is coupled to ground through the series combination of biasing resistors 61 and 62. Control grid 55 is coupled to the junction of resistors 61 and 62 through a voltage divider comprising resistors 63 and 64. The junction of resistors 63 and 64 is coupled to ground through a variable capacitor 65. Anode 66 of tube 56 is coupled to a source of positive potential through a resistor 67 and to terminal A.

The other detector-amplifier stages are identical with the stage described and hence will not be described in detail. It is important to note, however, that the point in each stage corresponding to the junction of resistors 63 and 64 is coupled to the same terminal of capacitor 65. Therefore, a portion of the output signal of each amplifier tube will appear across capacitor 65 and will be applied to the control grids of each of the amplifier tubes. The magnitude of the voltage thus applied may be adjusted by varying the value of capacitor 65. The phase of this voltage is such as to suppress the long term cross-talk in each of the stages. It is evident that the more nearly equal the cross-talk in each stage produced by distortion in one channel, the more complete will be the suppression of long term cross-talk.

While the invention has been described in a particular embodiment thereof and in a particular use, it is not desired that it be limited thereto, for obvious modifications thereof will occur to those skilled in the art with-

out departing from the spirit and scope of the invention as set forth in the appended claims.

What is claimed is:

1. A multi-channel pulse modulation system receiver, comprising phase shifting means having an input circuit and an output circuit and being arranged to shift the phase of frequencies lying within a first given range with respect to the phase of frequencies lying within a second given range lower than said first given range, means to apply received pulses having sloping leading and trailing edges and including frequency components lying within said first and second given ranges to the input circuit of said phase shifting means thereby substantially to steepen the leading edges of said received pulses, a differentiating network coupled to the output circuit of said phase shifting means, said network including means to differentiate said pulses thereby to produce correcting pulses, means to combine said correcting pulses and said received pulses thereby substantially to steepen the trailing edges of said received pulses, a plurality of receiving channels, means including an electronic distributor arranged to commutate said receiving channels, means coupled to said combining means to apply said received pulses to said electronic distributor, means coupled to said receiving channels to derive therefrom modulation components proportional to long-term cross-talk present in said receiving channels, and means to apply said modulation components to each of said receiving channels in a sense to suppress long-term cross-talk therein.

2. A multi-channel pulse modulation system receiver, comprising phase shifting means having an input circuit and an output circuit and being arranged to shift the phase of frequencies lying within a first given range with respect to the phase of frequencies lying within a second given range lower than said first given range, means to apply received pulses having sloping leading and trailing edges and including frequency components lying within said first and second given ranges to the input circuit of said phase shifting means thereby substantially to steepen the leading edges of said received pulses, capacitive means coupled to the output circuit of said phase shifting means selectively to attenuate the frequency components of said received pulses lying within said first given range, a differentiating network coupled to the output circuit of said phase shifting means, said network including means to differentiate said pulses thereby to produce correcting pulses, means to combine said correcting pulses and said received pulses thereby substantially to steepen the trailing edges of said received pulses, a plurality of receiving channels, means including an electronic distributor arranged to commutate said receiving channels, means coupled to said combining means to apply said received pulses to said electronic distributor, means coupled to said receiving channels to derive therefrom modulation components proportional to long-term cross-

50
55

talk present in said receiving channels, and means to apply said modulation components to each of said receiving channels in a sense to suppress long-term cross-talk therein.

5 3. In a multi-channel pulse modulation system receiver, comprising circuit means to receive signal pulses having a sloping trailing edge, an electron discharge tube having a control grid coupled to said circuit means, means including a differentiating network connected in 10 the power circuit of said electron discharge tube, said network including means to differentiate said signal pulses thereby to produce correcting pulses, means to combine said correcting pulses and said received signal pulses thereby to steepen the trailing edges of said received signal pulses, an electronic distributor, second circuit means coupled to the output of said electron discharge tube and to said electronic distributor, a plurality of receiving channels, means coupling said receiving channels to said electronic distributor.

15 4. The combination set forth in claim 3 including means coupled to said receiving channels to derive therefrom modulation components proportional to long-term cross-talk present in said receiving channels, and means to apply said modulation components to each of said receiving channels to suppress long-term cross-talk.

20 5. In a multi-channel pulse modulation system receiver, the combination comprising circuit means to receive signal pulses, a phase shifting network having an input circuit coupled to said circuit means and an output coupled to an electron discharge tube, a differentiating network connected in the cathode circuit of said electron discharge tube, a plurality of receiving channels, an electronic distributor arranged to commutate said receiving channels, means coupled to the output circuit of 30 said electron discharge tube to apply said received pulses to said electronic distributor, means coupled to said receiving channels to derive therefrom modulation components proportional to long-term cross-talk present in said receiving channels, and means to apply said modulation components to each of said receiving channels to suppress long-term cross-talk.
